UNITED STATES PATENT OFFICE.

EMIL G. SAUER, OF RICHMOND HILL, NEW YORK, ASSIGNOR TO BIGELOW CARPET COMPANY, A CORPORATION OF MASSACHUSETTS.

DESIGN FOR CARPET.

40,438.

Specification for Design.

Patented Jan. 11, 1910.

Application filed November 13, 1909. Serial No. 527,963. Term of patent 3½ years.

To all whom it may concern:

Be it known that I, EMIL G. SAUER, a citizen of the United States, residing at Richmond Hill, in the county of Queens and State of New York, have invented a new, original, and ornamental Design for Carpets, of which the following is a specification, reference being had to the accompanying drawing, forming part thereof.

The figure is a plan view of a carpet, showing my new design.

I claim:

The ornamental design for a carpet, as shown.

EMIL G. SAUER.
